UNITED STATES PATENT OFFICE.

FRANK L. SESSIONS, OF COLUMBUS, OHIO, ASSIGNOR TO THE JEFFREY MANUFACTURING COMPANY, A CORPORATION OF OHIO.

MINING-MACHINE.

1,247,459.

Specification of Letters Patent. Patented Nov. 20, 1917.

Application filed March 23, 1910, Serial No. 551,068. Renewed May 25, 1917. Serial No. 170,983.

To all whom it may concern:

Be it known that I, FRANK L. SESSIONS, a citizen of the United States, residing at Columbus, in the county of Franklin and 5 State of Ohio, have invented certain new and useful Improvements in Mining-Machines, of which the following is a specification, reference being had therein to the accompanying drawing.

10 The invention relates to machines for cutting a horizontally extending kerf in the coal, or other material to be mined, preparatory to blasting or breaking the coal from the solid. More particularly the invention 15 has to do with machines of the side cutting type which are especially adapted for use in room and pillar mining. These machines have a main frame and cutting apparatus rigidly mounted on and projecting from the 20 inner end of the frame. In operation the frame slides over the floor of the mine, the machine being propelled along the face by a cable or the like which exerts a draft on the main frame at points adjacent the coal 25 face, while the cutters are held to the work by guiding devices comprising a cable or the like which is arranged to exert a rearward draft on the outer part of the main frame and which is paid out under a resistance, variable at the will of the operator, as 30 the machine advances.

The object of my present invention is to improve the last named devices for guiding the machine or holding it to its work by 35 providing in connection with devices for offering a variable resistance to the paying out of the retarding cable, suitable means for positively stopping such paying out.

While my improvements, structurally 40 considered, relate to the retarding devices, functionally considered they are related to the machine in a more general way, and I therefore fully show and describe a machine embodying my invention.

45 Figure 1 is a plan view of a mining machine embodying my improvements.

Fig. 2 is a section on the line 2—2 of Fig. 1.

Fig. 3 is a side elevation of the machine.

50 Fig. 4 is a transverse section on the line 4—4 of Fig. 1.

Figs. 5 and 5^a are enlarged sections on the line 5—5, Fig. 1, showing the operating mechanism and the cutter frame respectively.

Fig. 6 is an enlarged section on the line 6—6, Fig. 1.

Fig. 7 is an enlarged section on the line 7—7, Fig. 1.

Fig. 8 is an outer end elevation of the friction held angling or guiding drum.

Fig. 9 is a side elevation of said drum.

Fig. 10 is a vertical section on the line 10—10, Fig. 8.

Fig. 11 is a detail sectional view taken on the line 11—11, Fig. 8.

Fig. 12 is a plan view on a small scale showing the machine in position near the right rib of a mine room to begin the entering or sumping cut.

Fig. 13 is a similar view of the machine with the sumping cut partially completed.

Fig. 14 is a similar view showing the machine when the sumping cut has been completed.

Fig. 15 is a plan view on a small scale showing the machine as it is propelled across the room along the coal face to make the under cut.

For the purposes of illustration I have shown in the drawing a mining machine of which A indicates the main frame as an entirety, B the cutting apparatus extending laterally therefrom and supported thereby, C, C' the feeding and guiding mechanism 85 for advancing the cutting apparatus and machine either longitudinally or laterally, D the motor mechanism, and E the auxiliary parts employed when it is desired to have the cutting apparatus advanced into the coal 90 transversely to the face thereof.

The main frame may be of any suitable construction. I have shown it comprising a shoe 1 adapted to rest upon the ground with freedom to slide freely in all directions, longitudinally arranged angle bars or plates 2, 2 secured to said shoe at either side thereof and a suitable platform 3 resting upon and secured to said longitudinal side bars. 4, 4 are webs or plates depending from the platform 3 and carrying at their lower ends the laterally turned longitudinally extending cutting apparatus guides 5, 5.

The cutting apparatus comprises a longitudinally arranged horizontally disposed base plate 6, two longitudinally arranged horizontally disposed guide plates 7 above said base plate and spaced therefrom by the longitudinally arranged bars 8 so as to form a chain guide or recess 9, the parts just re- 110

ferred to being secured together in any suitable manner, as by rivets 10. 11 is an inner sprocket wheel mounted upon a vertical axle 11', and between the inner end of the base 5 plate 6 and a top plate 12 suitably secured to the base plate and having an outwardly extending centrally arranged part 12' fitted snugly between the top bars 7, 7 of the chain frame.

10 The motor D is suitably secured upon the platform 3 with its armature shaft 13 arranged longitudinally of the machine. 14 is a longitudinally arranged shaft, preferably having its axis in the vertical longitudinal 15 plane of the axis of the chain frame. It is suitably mounted near either end in bearings 14' and 14'', one of which is carried by a bearing standard 14^a suitably secured to the platform 3. The standard 14^a extends 20 transversely of the machine in either direction from the shaft 14 for the purpose to be hereinafter described. 15 is a spur gear rigidly secured to the shaft 14 and meshing with a pinion 16 secured to the inner end 25 of the armature shaft 13. 17 is a bevel pinion loosely mounted on the shaft 14 near the outer end thereof. 18 indicates a positive clutch interposed between the said shaft 14 and the bevel pinion 17, the longitudinally 30 stationary element 18' of said clutch being secured to the said bevel pinion and the longitudinally movable element 18^a being splined to the shaft. 18^b indicates suitable mechanism for moving the element 18^a of 35 the clutch in either direction.

19 is a vertically disposed shaft suitably mounted in bearings carried by the main frame of the machine and having its axis in the vertical plane containing the axis 40 of the shaft 14. 20 is a bevel gear secured to the upper end of the said vertical shaft and in mesh with the bevel pinion 17. 21 is a sprocket drive wheel rigidly secured to the lower end of the vertical shaft 19.

45 22 indicates as an entirety an endless cutter chain or carrier extending around the sprocket drive wheel 21 and the inner sprocket 11 carried by the cutter frame, it being arranged at either side within the 50 guides 9 of the said cutter frame and carrying laterally extending cutters 23 of any suitable construction. The cutter frame is supported from the main frame by the longitudinally arranged slides or guides 5 depending from the main frame and arranged to fit snugly between the base plate and the upper plate of the chain frame. The main frame and the chain frame are normally held from longitudinal movement relative to 60 each other by mechanism indicated as an entirety by 24, which also serves as an adjusting means for moving the frames relative to each other to vary the tension upon the cutter chain. The adjusting mechanism 65 24 comprises a longitudinally arranged

screw threaded shaft 24' mounted near its inner end in a bearing in a depending plate 25 which is secured to the inner end of the main frame platform 3. Near its outer end it is fitted into a threaded nut 26 which is 70 arranged between uprights or projections 27, 27' carried by the base plate 6. The inner end of this shaft is squared as indicated at 24^b to receive a suitable wrench for turning the shaft in either direction so as to 75 extend the chain frame relative to the main frame or to force it in the opposite direction relatively thereto, as desired.

28 is a worm gear rigidly secured to the longitudinally arranged shaft 14 near the 80 inner end thereof and between the bearing standard 14^a and the gear wheel 15 secured to the said shaft. 29 is a shaft arranged beneath the said shaft 14 and transversely of the main frame. It is suitably mounted in 85 a bearing 29' secured to the platform of the said frame. 30 is a worm wheel secured to the inside end of the said transverse shaft 29 and in mesh with the worm 28 on the shaft 14. 31 is a worm rigidly secured to 90 the outside end of the shaft 29.

32 is a longitudinally arranged shaft mounted near either end in bearings 32', 32'', carried by bearing standards 14^a and 32^a, the latter being arranged parallel to the former 95 and of substantially the same width and secured to the platform of the main frame. The axis of this shaft 32 is in a vertical longitudinal plane on the opposite side of the vertical longitudinal plane of the axis 100 of the shaft 14 from armature shaft 13. 33 is a worm wheel rigidly secured to the outer end of the shaft 32 and in mesh with the worm 31 on the transverse shaft 29. 34 is a spur gear loosely mounted upon the shaft 105 32 adjacent to the bearing standard 14^a, and 35 is a gear wheel of greater diameter than the gear wheel 34 and loosely mounted upon the said shaft 32 adjacent to the bearing standard 32^a. 36 indicates as an entirety 110 clutch mechanism for alternately connecting the gears 34 and 35 to the shaft 32. Of this clutch mechanism 36' indicates a longitudinally movable element splined to the shaft 32 and carrying at one end clutch jaws 36^a adapted to engage clutch jaws 36^b secured to the gear wheel 35 and at its other end clutch jaws 36^c adapted to engage with the clutch jaws 36^d carried by the gear wheel 34. 37 indicates as an entirety 115 suitable mechanism for shifting the movable element 36' of the clutch in either direction at will. 38 is a longitudinally arranged drum 120 shaft suitably mounted near either end in 125 bearings 38', 38^a in the bearing standards, 14^a and 32^a respectively. The axis of the shaft is on the opposite side of the vertical plane containing the axis of the shaft 14 from the axis of the shaft 32. 39 is a gear 130

120

wheel rigidly secured to the shaft 38 near the outer end thereof and in mesh with the gear wheel 34 on the shaft 32, and 40 is a gear wheel of smaller diameter than the 5 gear wheel 39 rigidly secured to the inner part of the shaft 38 in position to mesh with the gear wheel 35 on the shaft 32.

41 is a cable winding drum loosely mounted on the shaft 38 and preferably adjacent 10 to the gear wheel 40 at the inner end thereof. The periphery of the cable drum may be spirally grooved as indicated at 41' to assist in the spooling of a draft cable upon the drum. The drum is preferably connected 15 to the shaft 38 by means of a friction clutch 41^a, one element of which is a ring or casing 41^b carried by the drum and extending outwardly therefrom, and the other element of which is a pulley or ring 20 41^c having its rim radially slotted at 41^d, 41^d, as indicated. 41^e are adjustable wedges or expanders arranged between the sections of the rim at said slots and adapted to force the periphery of the rim into engagement 25 with the inner walls of the ring 41^b in the well known manner. By varying the adjustment of the expanders, the clutch can be made to slip when the resistance to the rotation of the winding drum reaches any 30 given amount. 43 is a pulley or sheave arranged to receive and guide the cable 44 as it is wound upon or is paid out from the drum 41. This pulley 43 is mounted in a swiveling support having a spindle mounted 35 in a bracket bearing 43'. The pulley spindle can be turned so that the pulley can be made to lie in either of several planes. When the machine is in operation and is being bodily advanced along the face of the coal the 40 pulley is substantially at right angles to the longitudinal lines of the machine. When the machine is being advanced longitudinally to make the sumping cut the pulley is turned into its outward 45 position, as shown in Figs. 12, 13 and 14, as will be more fully described presently. The pulley may in fact be made to take any angular position, within a range of about 180°, as may be desired, in moving the 50 machine about under its own power by means of the draft cable 44. Thus when it is desired to unload the machine from the truck on which it is transported from room to room, the pulley may be turned inward and the draft cable made fast at some point in 55 front of the machine to draw the machine from the truck. In order to have the pulley 43 automatically assume the most advantageous position when stress is being exerted 60 upon the cable, the pulley support or carrier is so constructed as to hold the pulley axis in a plane other than the plane of the axis of the spindle part. In other words, the pulley carrier is similar to the fork 65 carrier of a caster wheel.

For the purpose of guiding the machine or assisting to guide it while it is being propelled laterally along the face of the coal, I employ a supplemental cable 45 and a drum 46 upon which said cable may be wound. This drum is mounted upon a bracket 47 on the outer end of the machine, said bracket being provided with a horizontally and outwardly extending hub or stub shaft 48, upon which the drum 46 turns. 75 The drum is held in position upon the shaft 48 by means of screw bolt 49. In addition to the groove or recessed part 46^a of the drum upon which the cable is wound, a cylindrical extension 50 is provided with 80 which a flexible brake band 51 coöperates. Clamping lugs 52 and 53 are riveted or otherwise secured to the respective ends of the brake band 51. These lugs are perforated to receive a clamping bolt or screw 85 54 and the lug 53 is slotted to receive a nut 55. This nut, when the parts are in position as shown in Fig. 8, engages the bottom of the slot formed in the lug 53 so that it cannot turn. And thus by turning the bolt 90 54 one way or the other the brake band may be tightened or loosened as desired. As a convenient means for turning the screw bolt 54 a handle 56 is pivotally secured to the end of said bolt. A partial revolution of the 95 bolt can be made with the handle and then by swinging the handle on its pivot the turning movement can be continued. The lug 52 is formed with a vertical extension or flange 52^a which is perforated so as to 100 pass over a cylindrical boss 57 on the bracket 47, and the brake band is thus prevented from being bodily displaced.

At times it is desirable to positively lock the drum against rotation independently of 105 the brake band. To this end a locking pin 58 is slidably mounted in the bracket 47, as shown in Figs. 8 and 9, in position to engage any one of a series of holes or sockets 59 formed in the adjacent face of the drum 46 110 or of its extension 50. The pin 58 is pivotally connected to a hand lever 60 by means of which it can be readily moved into and out of locking position.

The shaft 48 upon which the drum is 115 mounted is preferably formed with suitable ducts 61 through which oil may flow to the bearing surfaces of the drum, and a duct 62 may be formed in the bracket 47 through which oil may be supplied to the duct 61. 120

For the purpose of feeding and guiding the machine during the initial or sumping cut I provide the following devices. 63 is a guide frame which comprises a bottom part or shoe 64 designed to slide over the 125 floor of the mine and an upper transverse bridge part 65 which rests upon the shoe 64 and spans the cutter frame in the manner shown in Fig. 4. The transverse frame part 65 carries a depending guide bracket 65^a, 130

which extends between and slidably engages the side bars or plates 6 and 7 of the cutter frame, a relative sliding movement between the guide frame and the cutter frame of the machine being thus provided for. The extent of this movement is indicated in Figs. 12 and 13, which show the extreme positions of the guide frame in relation to the machine. The bridge part 65 is provided at its ends with upstanding rounded lugs 65^a, 65^b which are adapted to receive the lower ends of screw jacks, such as 66 (see Fig. 12), which may be set between the guide frame 63 and the roof of the mine so as to clamp the guide frame rigidly on the floor of the mine, or at least hold it against movement transverse of the machine.

In order that the winding cable 44, may be efficiently used, in connection with the guide frame 63 for making the sumping cut, the main frame of the machine is preferably provided with guide sheaves or pulleys 67, 68 and 69. The cable 44 may be extended outward from the swiveled pulley 43, passed around the pulleys 67 and 68 and thence extended inward over pulleys 69 to a suitable anchoring device, such as a jack at 70.

The manner in which my improved machine operates will readily be understood from the above description. Assuming that it is desired to under-cut the face of the coal in a room of a mine which is operated on the "room and pillar" plan, the machine is first put into the position shown in Fig. 12 adjacent the right rib and with the cutting apparatus directed toward the face of the coal to be under cut. The guide frame 63 having been moved inward as far as it will go in relation to the cutter frame is now jacked down, as indicated in Fig. 12, the draft cable 44 is passed outward over the guide pulleys 67 and 68 on the rear corners of the machine and thence inward over the guide pulley 69 on the right side of the machine to the jack 70. Current now being applied to the motor, it is set in operation and drives the shaft and gearing down to and including the clutch element at 18^a and 50 also the clutch element at 36. The operator upon shifting these drive clutch elements into engagement with their companion parts causes the power to be transmitted first to the cutting apparatus and secondly to the 55 winding drum 41. Thereupon the machine as an entirety is drawn endwise toward and against the coal. As the cutters engage the coal the re-action tends to swing the inner end of the machine to the right, but such 60 movement is prevented by the guide frame 63, which is effective for this purpose until the main frame of the machine is advanced into engagement with the guide frame at which point the motor is stopped. The position of the machine at this time is shown in

Fig. 13. The cutters are now so far under the coal that further guidance by the frame 63 is not essential. Accordingly, the jack 66 having been removed the motor is again started and the remainder of the sumping 70 cut is completed bringing the machine into the position shown in Fig. 14. During the latter part of the sumping cut it will be understood, of course, that the guide frame 63 moves bodily with the machine. 75

The initial or sumping cut having been made in the manner stated, the machine is next propelled laterally along the face of the coal to effect the under cutting in the following manner. The cable 44 is detached 80 from the jack 70 and stretched along the face of the coal to the left rib where it is made fast to an anchor as, for example, a jack 71. The end of cable 45 is now made fast to the jack 70, which, if necessary, may 85 be re-set in a position more nearly opposite the friction drum 46. The motor is now started, or if the motor has been running idle the clutch elements 18^a and 36 are thrown into operative position whereupon 90 the cutters begin to move and the winding drum 41 to rotate. The rotation of drum 41 draws upon the cable 44 so that the machine is gradually fed laterally along the face of the coal, the cutters meanwhile effecting the 95 under cut. The position of the machine during this operation is indicated in Fig. 15. If the machine during this operation were subjected only to the draft force of the cable 44 and to the re-action of the coal upon the 100 cutters the rear end of the machine would tend to swing around to the left and the cutters would not be held up to their work. This, however, is prevented by the cable 45 which is paid out against the friction of 105 brake band 51 upon the extension 50 of the drum 46. This frictional force, and therefore the tension in cable 45, can be varied at will by simply adjusting the clamping bolt 54 of the brake. The operator thus has 110 within his control a very simple yet efficient and convenient means for controlling the angular position of the machine in relation to the coal face. If the outer end of the machine tends to swing too much to the 115 left, due to the encountering of a hard streak of coal or hard foreign materials in the coal, it is only necessary to tighten the brake band of drum 46 to sufficiently retard the outer end of the machine. On the other 120 hand, when the cutters move into softer material and the inner end of the machine tends to feed too rapidly in relation to the end, it is only necessary to loosen the brake band somewhat. 125

In the operation of the machine as above described, it is desirable at times to angle the machine quickly and to a considerable extent. It is to accomplish this in an efficient and satisfactory manner without inter- 130

fering with the normal functions of the friction brake that I have provided the positive lock devices. When it becomes desirable to quickly swing the inner end of the machine forward, the locking pin 58 can be thrown into engagement with the winding drum 46 so as to positively lock the latter against rotation. The outer rear corner of the machine then becomes a practically stationary pivot point about which the inner end of the main frame and the cutting apparatus are swung forward by the draft of the propelling cable 44. When the machine has in this manner been swung into the desired position in relation to the coal face, the locking pin 58 is withdrawn from engagement with the cable reel and the machine is allowed to advance bodily under the control of the friction brake on drum 46. The provision of the positive lock for the drum 46 obviates the necessity of using the brake to effect a substantial locking of the drum, and this is advantageous as the brake tends to operate more reliably when the range of braking pressure or tension is not too great. It is obvious, furthermore, that the provision of the positive lock saves the braking apparatus from considerable wear and tear.

Occasion for the use of the positive lock devices may arise from time to time as the machine advances along the face, due to variation in the character of the material encountered by the cutters, but the lock is found especially advantageous in guiding the machine at the very beginning of the side cutting. It will be observed, upon referring to Fig. 14, that when the sumping cut is finished, the machine stands with its inner end angled somewhat rearward, the sumping cut being made at a slight angle to the side wall or rib in order to maintain the width of the room. But such an angular position of the machine is not suitable for making the under cut along the face, the proper angular position of the machine relative to the coal face being more nearly that shown in Fig. 15. Therefore, when the sumping cut is completed and the side cut is about to begin, the machine is angled from the position shown in Fig. 14 to that shown in Fig. 15, and this is readily accomplished by locking the winding drum 46 against rotation by means of the positive lock which I have provided. When the ma-

chine reaches the desired angle, as shown in Fig. 15, the positive lock is disengaged and the machine continues its advance under the control of the friction brake.

The means for guiding and controlling the machine while the entering or sumping cut is being made, as set forth in this application, were invented by me but I make no claim to said means herein as they form the subject-matter of my co-pending application, Serial No. 567,201, filed June 16, 1910.

What I claim is,

1. In a mining machine, the combination of a main frame, cutting apparatus projecting from the inner end of said frame, a flexible draft device acting on the inner end of the main frame to propel the machine along the face of the coal, and guiding means for resisting the advance of the outer part of the main frame comprising a cable reel on the main frame, a cable on said reel adapted to have one end anchored to a stationary holder on the rear side of the machine, an adjustable brake device adapted to offer a variable resistance to the rotation of the reel, and means operable independently of the brake device for positively locking the reel against rotation.

2. In a mining machine, the combination of a main frame, cutting apparatus projecting from the inner end of said frame, a flexible draft device acting on the inner end of the main frame to propel the machine along the face of the coal, and guiding means for resisting the advance of the outer part of the main frame comprising a bracket rigidly mounted on the main frame, a cable reel mounted on said bracket, a cable on said reel adapted to have one end anchored to a stationary holder on the rear side of the machine, an adjustable brake device adapted to offer a variable resistance to the rotation of the reel, and means operable independently of the brake device for positively locking the reel consisting of a bolt slidably mounted in the said bracket and recesses in the reel adapted to receive the end of the bolt.

In testimony whereof I affix my signature, in presence of two witnesses.

FRANK L. SESSIONS.
